UNITED STATES PATENT OFFICE

132,908

DESIGN FOR A PURCHASER'S PROFIT- SHARING INDICATOR OR THE LIKE

John William Goehring, Browns Valley, Minn.

Application December 30, 1941, Serial No. 104,919

Term of patent 14 years

To all whom it may concern:

Be it known that I, John William Goehring, a citizen of the United States, residing at Browns Valley, in the county of Traverse and State of Minnesota, have invented a new, original, and ornamental Design for a Purchaser's Profit-Sharing Indicator or the like, of which the following is a specification, reference being had to the accompanying drawing, forming part thereof.

I claim:

The ornamental design for a purchaser's profit-sharing indicator or the like, as shown.

JOHN WILLIAM GOEHRING.
